LOW TEMPERATURE LIQUID PUMP

Jiro Okada, Suginami-ku, Tokyo, Japan

Application December 18, 1934, Serial No. 758,084
In Japan May 1, 1934

2 Claims. (Cl. 103—203)

This invention relates to a low temperature liquid pump for pumping liquid which is easily vaporized at an atmospheric temperature, characterized in that, a pump body is hung in a low temperature liquid container to submerge the whole body in the liquid so that the body is always maintained at the same temperature with the liquid, said body having an opening at about 80% of the suction stroke of the piston to 5 let out vapour generated and liquid in said stroke from the opening, thus forcing out liquid only at the delivery stroke, and the invention has for its object to obtain a low temperature liquid pump having the most high efficiency for delivering easily vaporized liquid at an atmospheric 10 temperature.

An annexed drawing is a sectional elevation of a low temperature liquid pump according to the invention, showing the pump body and an arrangement of the pump.

In the invention the whole body of a pump for forcing out liquid easily vaporized at an atmospheric temperature is hung in the low temperature liquid in a vacuum container and is maintained always at the same temperature with the liquid, then the suction valve can be operated automatically or mechanically to suck in the low temperature liquid from the container due to its head at the suction stroke of the piston 25 without creating vacuum in the body, and vapour generated by an atmospheric temperature transmitted through the piston rod is discharged into the liquid in the said container through the opening formed at about 80% of the suction stroke, and when the body is full of liquid only, a certain quantity of liquid is discharged at the beginning of the delivery stroke from the opening, and after said opening is cut off by the piston, the liquid only is perfectly forced out thus the 30 maximum delivery efficiency of the pump being obtained, and constant and exact quantity of liquid being delivered per stroke.

When a liquid easily vaporized at an atmospheric temperature meets with a substance of room temperature, there occurs a violent vaporization, and in a pump of an ordinary type having the body exposed to the room temperature, the liquid is vaporized at once at the entrance of the suction valve and the pump cannot 45 suck in the liquid but only vapour at the suction stroke of the piston. And if the liquid might be brought in the suction valve the liquid is vaporized in the interior of the pump body without discharging any liquid from the delivery valve. In the present apparatus, however, the

whole pump body is submerged in the liquid and is maintained at the same temperature with the liquid, and the suction valve is opened mechanically, for example through lever and rod mechanism actuated by cam on the crank shaft, 5 to suck in freely the surrounding liquid to the pump body due to its head, thus isolating said body from the room temperature to avoid any vaporization.

But as the other end of the piston rod fitted 10 to the piston is exposed to the room temperature, the surface of the piston absorbs very slightly an external heat through heat transmission, so that a minute quantity of liquid is vaporized lowering the suction efficiency.

In order to prevent this phenomena, an opening as in internal combustion engine of two-cycle is formed extending from about 80% of the suction stroke to the end thereof (as shown in the drawing) so that, at the upper stroke of 20 the piston, the opening is opened and the body will make an intercourse freely with the surrounding low temperature liquid through the opening, and the vapour flows out of said opening, without retaining any vapour in the body. 25

The reason for providing the opening extending from about 80% of the suction stroke to the end thereof will be understood in a reciprocating pump of a definite crank radius, that an ample time necessary to let out the vapour 30 in the pump body from said opening can be obtained at that portion of the stroke, and also at the beginning of the delivery stroke, a certain quantity of the low temperature liquid is 35 fully discharged from said opening and, after the opening is cut off by the piston, the liquid only is forced out to obtain the maximum efficiency compared with apparatus with pump of former type.

The low temperature liquid container submerging the pump body therein consists of vacuum double walls for heat insulation as shown in the drawing with the outer wall covered with an insulating material, and cold vapour generated naturally from liquid in the container is led to the 40 space between the container and an outer casing, said space being also arranged with coil of the delivery pipe to insulate the container 45 from external heat.

In the annexed drawing, (1) is the body of a 50 pump according to the invention, having the piston (2) and the piston rod (3). In order to submerge a pump body in a low temperature liquid container (4), the body is hung by rods (6) which are fitted to a frame (5), said rods hav- 55

ing a suitable length to minimize the quantity of heat transmitted from said frame due to heat conductivity, or the rods may be substituted by chains for the same purpose. Now, a certain 5 quantity of a low temperature liquid (7) is filled in the container (4), and after the body is cooled down to the same temperature with said liquid, the suction valve (9) is opened mechanically by operating a lever (8) through a valve mechanism, 10 and the liquid (7) enters into the pump body from the suction port (16) due to its head so that the body will be full of the liquid by displacement of the piston. The valve (9) may be opened automatically by the suction stroke of the piston 15 to suck in the liquid (7). When the piston (2) reaches the openings (11) extending from about 80% of the suction stroke to the end thereof, vapour, generated on account of heat transmitted from an external atmosphere through the 20 piston rods (3), flows out of the openings to the surrounding liquid, and the interior of the pump body will freely make an intercourse with said liquid without allowing the existence of any vapour in the body.

25 At the beginning of the delivery stroke of the piston, a certain quantity of liquid in the body flows out of said openings (11) and after the piston cuts off the openings the liquid only is discharged from the delivery valve (12) to a 30 pipe (13) which is wound in the space (15) between the container (4) and heat insulating wall (14) of outer casing, thus cooling the space, and is led to required position. And cold vapour generated naturally from the surface of the liquid (7) of the container (4) through an opening (17) overflows down in said space (15), protecting the space from entry of the external heat, 35 and then it is discharged from a port (16). A

plate (19) of heat insulating material may be fitted on the projections (18) of the frame (5).

The pump according to the invention is not only used for low temperature liquid, but it may be operated for high temperature liquid with 5 similar effect.

I claim:

1. A low temperature liquid pump comprising in combination an engine supporting frame, the lower part of which forms a casing, an insulated vacuum container supported within said casing and filled with a low temperature liquid, a pump body including a hollow cylinder open at its upper end, a piston operating therein, said cylinder having at least one opening in its wall 15 situated at about 80% of the suction stroke of the piston, inlet and outlet valves at the lower end of the cylinder, an outlet pipe leading from the outlet valve to carry the liquid from the vacuum container and means for suspending the 20 pump body within the container including a heat-resisting plate fastened to the top of the casing and rods attached at their upper ends to the plate and at their lower ends to the pump body, said rods being of such length that the pump 25 body is completely submerged in the low temperature liquid contained within the vacuum container.

2. A low temperature liquid pump as claimed in claim 1, wherein the insulated container includes an air tight outer casing, an inner double-walled casing having an open top so as to be filled with liquid and the outlet pipe being coiled around the outer surface of the inner casing to facilitate cooling of the liquid contained in the 30 inner casing.

JIRO OKADA.
